READING SUPPORT

Filed Aug. 12, 1929

FIG. 1.

UNITED STATES PATENT OFFICE

KARL DRAXLER, OF LOS ANGELES, CALIFORNIA

READING SUPPORT

Application filed August 12, 1929. Serial No. 385,258.

This invention relates to devices used for holding reading matter in a desirable position before the eyes of a reader.

One of the objects of this invention is to provide a support in form of a foldable cover by which such reading matter as for instance a stenographer's note-book can be held in a suitably upright position to be easily readable by a stenographer sitting before a typewriter.

Another object is to provide such a support with an interconnecting folding link to which the bound edge of a note-book can be held in such a manner that the page on which reading matter is to be observed appears in a suitably evenly flat condition to insure equally well against any light-reflection over the whole page.

Another object is to provide such a support or holder with friction means along the interconnecting edges of the oppositely disposed covers that the foldable covers can be placed at any desired angle on the table top to make supported reading matter distinctly readable without undue strain on the eyes due to light reflections.

Another object is to provide adjusting means for the frictional interconnection between the covers.

Another object is to provide a follower on the support by which certain lines or matter of the supported matter can be checked.

Another object is to provide attachments by which any desired matter can be held on the support.

Other objects will appear from the following description and appended claims as well as from the accompanying drawing, in which—

Fig. 1 is a top plan view of a support unfolded having various attachments to jointly or separately operate according to this invention.

Fig. 2 is a perspective view of the support folded backward with a book indicated or outlined on one of the attachments of the support.

Fig. 3 is a perspective view of the support illustrating the use of another attachment

for holding small notes or cards on the support.

Fig. 4 is a perspective view of the support illustrating the flexibility of the back of the covers where by an inserted note-book 55 can be held so that the whole page is evenly flat on the support.

Fig. 5 is a detail edge view of the follower adapted to roll along the edges of the support and to cross over inserted reading 60 matter.

Fig. 6 is a cross section on line 6—6 of Fig. 1 illustrating the clamping feature of the interconnecting link between the covers.

Fig. 7 is a cross section on line 7—7 of Fig. 1 through the larger cross bars in the oppositely disposed frame structures of the covers.

As illustrated, the support consists principally of the two back covers 8 and 9 interconnected by the link-back 10.

Each of the covers is made of a frame structure consisting of the thinner bars 11, extending around four sides of the covers, a comparatively thicker bar 12 in one end of each of the covers, and the sheet material covering indicated at 13.

The edges of the sheet material are rolled in, by which the bars 11 are firmly embedded in the covers.

The engagement of the rolled-in edge of the link-back 10 around the end bar 12 is in form of a friction joint, the bar 12 being turnable within the rolled-in edge of the back, however, with a desired frictional grip, 85 by which the joints between the back 10 and the two covers 8 and 9 are made useful.

This frictional grip between the back and the covers is one of the principal features of this invention and the end bar 12 is for this reason made particularly thick to assure a desired amount of friction in these joints.

Making the bar 12 especially thick, and rolling the edges of the back suitably tight to insure the desired friction normally provides sufficient friction surface to insure a satisfactory grip between the back and the cover. However, in cases where particularly secure gripping is desired, clamping means are added in the joint structure, in Figs. 1 100

and 6 small clamping bolts 14 being indicated with washers 15 so disposed that the adjacent edges 16 can be pressed towards the flat portion 17 of the back 10.

5 To make the whole device convenient as well as attractive, a pencil container 18 is added in the structure of one of the covers as well as a mirror 20 and a container 19 for articles such as a powder puff, to eliminate other articles from the desk of a stenographer.

15 For properly supporting a book on the device, a shiftable brace 21 is provided, by which a book can be held in the manner illustrated in Fig. 2. In the form illustrated and indicated in Fig. 1, this brace is made of a single piece of wire, twisted so as to form the supporting hooks 22 in the front portion of the brace.

20 A small clip 23 pivotally secured at 24 to one of the covers serves to hold small cards and notes in the manner illustrated in Fig. 3.

25 To assist a reader in following reading matter from line to line, a follower or guide is provided as illustrated in Figs. 1, 4 and 5. Rollers 25 are mounted in suitable frames 26, which are connected by a cross bar 27 to reach across the whole width of the device, the rollers to run along the opposite upright edges of the cover so as to guide the cross bar 27 in a horizontal position up and down over the cover.

30 For holding a stenographer's note-book on the cover in the manner illustrated in Fig. 4, a spring 28 is drawn from side to side over the back 10 of the device, and, by the flexibility and adjustability of the covers with respect to the back 10, the covers can be adjusted so that the back is practically in alignment 35 with the front cover so that the supported note book appears evenly flat from its bound back down to the edge of the opened note-book portion from which a reading is desired.

40 Having thus described my invention, I claim:

1. In a support of the class described, a back portion rolled-in upon itself along the opposite edges, and covers having each a portion along one edge to firmly but turnably engage within the rolled-in edges of the back portion to be held thereby in adjusted positions, one cover with respect to the other and with respect to the back.

45 2. In a support of the class described, a back, covers swingably and adjustably connected to the opposite edges of the back, and clamping means in the back by which the connecting portions of the covers can be firmly clinched and adapted to yield to a certain amount of force for turning movements of said portions within the back so that the covers can be swung with respect to one another and with respect to the back.

50 3. In a reading support, a back made of

sheet material rolled in upon itself along the opposite edges, and adjusting means in the back between the spaced edges for jointly clamping the edges with respect to the larger central portion of the back so that the 70 rolled in portions can be contracted more or less.

4. In a reading support, a back made of sheet material rolled in upon itself along the opposite edges, covers having each a bar-like member along one edge of comparatively large diameter to provide friction surfaces for frictional engagement within the said rolled-in edges, and adjusting means in the back between the spaced edges for jointly 80 clamping the edges so as to result in a certain contraction of the rolled-in portions for adjustably holding the frictionally engaged covers.

5. In testimony that I claim the foregoing as my invention I have signed my name.

KARL DRAXLER.
